(21) Appl. No.: **29/913,236**
(22) Filed: **Sep. 28, 2023**

(57) **CLAIM**

(30) **Foreign Application Priority Data**

The ornamental design for a tread band portion for a motorcycle tire, as shown and described.

Mar. 30, 2023 (EM) 015016259-0007

DESCRIPTION

(51) **LOC (15) Cl.** **12-15**

(52) **U.S. Cl.**

USPC **D12/535**

(58) **Field of Classification Search**

USPC D12/535, 551, 555, 564

See application file for complete search history.

(56) **References Cited**

FIG. 1 is a front, right perspective view of a tread band portion for a motorcycle tire, showing our new design; FIG. 2 is a top plan view thereof; FIG. 3 is a bottom plan view thereof; FIG. 4 is a front elevation view thereof; FIG. 5 is a back elevation view thereof; FIG. 6 is a left side view thereof; and, FIG. 7 is a right side view thereof.

The portions of the tire depicted in long broken dashed lines of even length form no part of the claimed design.
